UNITED STATES PATENT OFFICE.

ADA HIBBITT, OF FORT RILEY, KANSAS.

ENVELOPE.

Application filed September 9, 1925. Serial No. 55,394.

This invention relates to improvements in envelopes and contemplates the provision of an auxiliary pocket arranged upon the corresponding side of the envelope for the reception of the envelope flap therein and adapted for association with the locking plate mounted for reciprocation therein whereby the locking plate when moved downwardly will in turn position the envelope flap within the auxiliary pocket in a locked position. Another object of my invention is the provision of a latch plate arranged upon the outer side of the envelope within the auxiliary pocket and including a plurality of super-imposed ears struck from the body thereof and adapted for selective engagement within the slotted portion provided in the locking plate when the latter is moved downwardly in a locked position whereby unauthorized inspection of the envelope's contents may be readily and easily detected owing to the fact that the locking plates will be torn loose when the envelope is opened.

With the above and other objects in view, the invention further includes the following novel features and details of construction, to be hereinafter more fully described, illustrated in the accompanying drawings and pointed out in the appended claims.

In the drawings:—

Figure 1 is a side elevation of the envelope with the flap in an open position. Figure 2 is a similar view with the flap closed. Figure 3 is a side elevation of the envelope with the auxiliary pocket broken away and disclosing the contents thereof. Figure 4 is a similar view of the envelope and the envelope flap arranged in a locked position within the auxiliary pocket.

Figure 5 is a vertical sectional view taken on line 5—5 of Figure 4.

Figure 6 is a longitudinal sectional view taken on line 6—6 of Figure 4.

Figure 7 is an elevation of the locking flaps.

Figure 8 is a similar view of the latch plate.

Referring to the drawings in detail, wherein like characters of reference denote corresponding parts, the reference character 10 indicates an envelope having an elongated extension 11 provided upon its flap 12 and which includes one portion of a snap

fastener as indicated at 13 upon its inner side, the purpose of which will be presently apparent.

Positioned upon the corresponding side of the envelope 10 with respect to the folding of the flap 12 and extension 11 carried thereby is an auxiliary pocket 14 having its upper end open for the reception of the extension 11 of the flap 12 therein.

An elongated locking plate 15 is positioned within the pocket 14 and having its respective side edges offset as indicated at 16 and secured to the corresponding side of the envelope 10 in defining a space 17 therebetween, the purpose of which will be presently apparent. The locking plate 15 has a row of superimposed ears 18 struck therefrom and extending outwardly and downwardly therefrom while a rectangular opening 19 is provided within the locking plate 15 immediately beneath the ears 18. The locking plate 15 is preferably formed of celluloid or some relatively stiff material in order that the ears 18 struck therefrom may not easily bend but remain in their downwardly and outwardly extending positions.

A latch plate having a substantial body portion and an elongated tab 21 extending therefrom is mounted for sliding movement within the pocket 14 upon the locking plate 15 and in accomplishing this mounting inwardly and downwardly oppositely disposed slotted portions 22 are provided within the lower portion of the circular body portion 20 thereof in order that the adjacent side edges of the rectangular opening 19 provided in the locking plate 15 may be received within these slotted portions 22 and the remaining lower portion of the circular body portion 20 extends rearwardly and slidably mounted upon the rear face of the locking plate 15.

The elongated tab or strip 21 extending from the circular body portion 20 of the latch plate or strip including the remaining half 23 of a snap fastener to accommodate its companion half 13 included upon the inner side of the elongated tab 11 of the envelope flap 12 and which elongated tab or strip 21 further includes an arcuate shaped opening 24 therein for selective reception of any one of the plurality of the super-imposed ears 18 provided upon the locking plate 15 immediately above the rectangular opening 19 provided therein whereby the said ear when received within the arcuate

shaped opening 24 will render it impossible to open the envelope without first tearing the circular body portion 20 of the latch plate from the elongated strip or tab 21 formed integral therewith. A cord or string as indicated at 25 depending from the lower free end of the circular body portion 20 of the latch plate extends through a keyhole opening 25' provided in the lower end of the locking plate 15 and extending through a correspondingly shaped opening 26 provided in the lower portion of the pocket 14 whereby the user may readily and easily pull this cord or string 25 therethrough in moving the latch plate downwardly to position any one of the plurality of super-imposed ears 18 within the arcuate shaped opening 24 provided therein, according to the displacement of the contents of the respective envelope.

It is thus to be noted from the foregoing description and accompanying drawings that this invention provides an exceedingly useful and advantageous envelope, the contents thereof being protected against unauthorized inspection without notice to the receiver owing to the fact that it is impossible to remove the contents of the envelope without first tearing the latch plate owing to the engagement of the respective ear 18 within the arcuate shaped opening 24 provided therein.

The invention is susceptible of various changes in its form, proportions and minor details of construction, and the right is herein reserved to make such changes as properly fall within the scope of the appended claims.

Having described my invention what is claimed is:

- 40 1. An envelope including a flap and having an extension tab extending from the flap, a pocket provided upon one side of the envelope and having its upper free end open for the reception of the tab therein, a locking plate arranged in spaced relation upon the envelope within the pocket and including a plurality of super-imposed downwardly and outwardly extending ears and a rectangular opening therein, and a latch plate 45 mounted for sliding movement upon the outer face of the locking plate and within the rectangular opening therein and having means provided upon its upper end for as-
- 50

sociation with the tab within the pocket.

2. An envelope including a flap comprising an extension tab extending centrally from the flap, a pocket provided upon one side of the envelope and having its upper side open for the reception of the tab therein, a locking plate arranged in spaced relation upon the envelope within the pocket and including a plurality of super-imposed downwardly and outwardly extending ears, and an elongated opening provided therein immediately beneath the ears, a latch plate having a circular body portion with inwardly, oppositely and downwardly disposed slotted portions therein for the reception of the adjacent and opposite side edges of the rectangular opening therein, and an elongated strip provided upon the upper portion of the latch plate including an arcuate shaped opening therein for the reception of the ears and associating means provided upon its upper end for associating the extension tab therewith.

3. An envelope including a flap comprising an extension tab extending centrally from the flap, a pocket provided upon one side of the envelope and having its upper side open for the reception of the tab therein, a locking plate arranged in spaced relation upon the envelope within the pocket and including a plurality of super-imposed downwardly and outwardly extending ears, an elongated opening provided therein immediately beneath the ears, a latch plate having a circular body portion with inwardly, oppositely and downwardly disposed slotted portions therein for the reception of the adjacent and opposite side edges of the rectangular opening therein, an elongated strip provided upon the upper portion of the latch plate including an arcuate shaped opening therein for the reception of the ears, means provided upon its upper end for associating the extension tab therewith, and a cord suspended from the lower edge of the circular body portion and extending through an opening provided in the pocket for the operation and reciprocatory movement of the former therein.

In testimony whereof I affix my signature.

MRS. ADA HIBBITT.
